Primary Examiner — Selina Sikder(74) *Attorney, Agent, or Firm* — Moyles IP, LLC(57) **CLAIM**

I claim the ornamental design of an asymmetric chair control panel, as shown and described.

DESCRIPTION

FIG. 1 is a front perspective view of an asymmetric chair control panel showing my new design;

FIG. 2 is a front view of the asymmetric chair control panel of FIG. 1;

FIG. 3 is a right side view of the asymmetric chair control panel of FIG. 1;

FIG. 4 is a left side view of the asymmetric chair control panel of FIG. 1;

FIG. 5 is a bottom view of the asymmetric chair control panel of FIG. 1;

FIG. 6 is a top view of the asymmetric chair control panel of FIG. 1;

FIG. 7 is a rear view of the asymmetric chair control panel of FIG. 1;

FIG. 8 is a front perspective view of an asymmetric chair control panel that is the mirror image of the asymmetric chair control panel of FIG. 1, for mounting on an opposite side of a chair; and,

FIG. 9 is a front view of the asymmetric chair control panel of FIG. 8.

The broken lines in the drawings of the asymmetric chair control panel are for the purpose of illustrating portions of the asymmetric chair control panel and form no part of the claimed design.
